(57) CLAIM

The ornamental design for a brush handle, as shown and described.

DESCRIPTION

FIG. 1 is a perspective view of a brush handle showing our new design;

FIG. 2 is a front side view thereof;

FIG. 3 is a back side view thereof;

FIG. 4 is a right side view thereof;

FIG. 5 is a left side view thereof;

FIG. 6 is a bottom view thereof;

FIG. 7 is a top view thereof; and,

FIG. 8 is a perspective view shown in condition of use.

In FIGS. 1–8, the broken lines are for purposes of illustrating portions of the brush handle, which form no part of the claimed design. The additional broken lines in FIG. 8 depicting a hand are to show the environment of use and form no part of the claimed design.

1 Claim, 5 Drawing Sheets
